PERMANENT MAGNET GALVANOMETER

Marvel W. Scheldorf, Schenectady, N. Y., assignor to General Electric Company, a corporation of New York

Application July 31, 1937, Serial No. 156,732

4 Claims. (Cl. 171—95)

My invention relates to permanent-magnet galvanometers of the balanced armature type, such as those employed in radio loud speakers, magnetic pick-up devices, electrocardiographs, and the like, and its object is to provide a galvanometer whose response is more nearly proportional to the variation of the current in its exciting winding than has been the case with prior galvanometers of this type.

The features of the invention which are believed to be novel and patentable will be pointed out in the claims appended hereto. For a better understanding of my invention, reference is made in the following description to the accompanying drawing wherein a side view of a preferred embodiment of my invention is illustrated.

The galvanometer illustrated is of the balanced armature type. It includes a pair of U-shaped soft-iron pole-piece parts 10 and 11 with their open sides facing each other but separated to provide a relatively large armature air gap in which a magnetic vane armature 12 is symmetrically mounted. The armature is biased to a central neutral position by suitable restraining means which may comprise a torsional rod 13 on which the armature is fixed at its center. The rod 13 may be clamped at one or both of its ends, one such clamp being indicated back of the armature at 14. An exciting winding 15 made in two coils 15 and 16 surrounds opposite end portions of the armature 12. These coils will be connected in series and excited by a current, such as the voice current of a radio loud speaker, tending to polarize the vane armature 12 in the direction of its length. Also a mirror 21 moved by the armature and a light ray indicating system such as a lamp 22 and scale 23 may be used.

A horseshoe-shaped permanent magnet 17 is provided to create a unidirectional magnetomotive force between the pole pieces of the two parts 10 and 11 as indicated by the designations "N" and "S". If now the excitation of coils 15 and 16 is such as to polarize the armature to produce a south pole at its right end and north pole at its left end as indicated, the armature will tend to twist counterclockwise and, if the exciting current is reversed, it will tend to turn in the opposite direction against the restraining force of the torsional shaft 13.

In the prior art device of this type, the permanent magnet 17 abutted directly against the soft-iron pole-piece parts 10 and 11 so that the only air gap of any consequence in the permanent magnet circuit was the gap between the pole pieces 10 and 11. Such prior art arrangement, while operative, was not very satisfactory for some purposes because the armature was quite unstable except, of course, in a central position with no exciting current flowing in coils 15 and

16. The armature had a strong tendency to snap over against and bridge the pole pieces, the position indicated in dotted lines, as soon as there was any current flow in the exciting winding. This tendency was due largely to the tendency 5 of the armature to move to close the only air gap in the permanent magnet flux circuit, and this tendency increased as the armature departed from a central position, making it impracticable to offset this magnetic pull by any 10 simple restraining device. For these reasons, the useful working range of the armature was quite limited and the deflecting force difficult to match and control by a restraining spring.

I have found that, if the permanent magnet 15 circuit is provided with additional air gaps, as, for example, by placing nonmagnetic spacers 18 and 19 between the permanent magnet 17 and the pole-piece parts 10 and 11, greatly improved results are obtained. The permanent magnet 20 must be of a larger size or produce a greater total flux than before because now appreciable flux leaks across between the pole pieces of the permanent magnet as indicated by the dotted lines 20. However, the improved results more 25 than offset the necessity of using a stronger permanent magnet.

It is evident that, with no reluctance gap or its equivalent at 18 and 19 when there is a deflection of the armature from neutral position 30 maximum reluctance, the permanent magnet flux increases and the magnetic pull on the armature increases not only because of the reduction in armature air gap reluctance with deflection but also because of the increase in permanent magnet flux with such decrease in reluctance; that is, there is a building up force condition that is difficult to control.

By increasing the reluctance of the permanent magnet flux circuit by the air gap at 18 and 19, the relative decrease in total reluctance of the magnetic circuit by movement of the armature from neutral is of a much lower order than before and the increase in permanent magnet flux is correspondingly less. The change in reluctance of the magnetic circuit due to rotation of the armature from maximum reluctance to a lower reluctance position is thus minimized. The instability of the armature is materially decreased and its sensitivity to current variations and its magnetic regulation characteristics greatly improved. It is possible to secure much better results by using a large magnet at 17 with the air gap at 18 and 19 than with a magnet weak enough to place directly on the pole-piece parts 50 45 50 55 60 65 70 length of air gap in series at 18 and 19 should preferably be not greater and may be less than the length of air gap between the north and south pole pieces of the galvanometer with armature 12 in the neutral position. The total length of air gap in the useful flux path should obviously not be greater and should preferably be less than the leakage flux gap at 20. With the relative dimensions shown in the drawing, 10 there is a negligible change in flux density across the armature air gap when the armature 12 moves from the neutral to an extreme position, and this useful flux is comparable in magnitude to the leakage of flux of the permanent magnet 15 17, the greater portion of which traverses the path indicated at 20. If I make gaps 18 much larger in proportion to the other gaps than here represented, beneficial results as regards stability will still be obtained but this will call 20 for a further increase in the size, strength and cost of the permanent magnet that ceases to be justifiable. The particular air gap dimensions and strength of flux to be used in any particular case will depend upon the degree of stability and sensitivity desired and the use for 25 which the device is intended.

The strength of the permanent magnet used may be such that the flux density in the useful air gap is increased in comparison to prior galvanometers of this general type. In such prior devices it was the practice to fit the pole pieces such as 11 and 12 to the permanent magnet as perfectly as possible. The result was that any increase in flux strength for the purpose of increasing sensitivity also decreased the stability. 30 I intentionally provide air gaps at points 18 and 19 and increase the strength of the permanent magnet used, but I do not wish to limit my invention to any particular gap dimensions and 35 strength of permanent magnet because any appreciable gap at the points 18 and 19 improves the relation between sensitivity and stability and is highly beneficial up to the point where this expedient becomes impracticable due to an unreasonable increase in size and cost of the permanent magnet.

In accordance with the usual practice, the magnet 17 is made of high grade permanent magnet material and is permanently magnetized to provide an efficient permanent magnet. The pole pieces 10 and 11 are made of soft iron and the armature 12 is preferably made of the best grade of soft, high permeability magnetic material obtainable.

55 By means of my invention, the useful range of vibration of the armature is increased, its deflection is more nearly proportional to the excitation current, and a more suitable restraining spring may be used.

60 It is evident that the structural relation of the parts may be materially changed without departing from the principle of the invention.

In accordance with the provisions of the patent statutes, I have described the principle of operation of my invention together with the apparatus which I now consider to represent the best embodiment thereof but I desire to have it understood that the apparatus shown is only illustrative and that the invention may be carried out by other means.

70 What I claim as new and desire to secure by Letters Patent of the United States is:

1. A galvanometer comprising, a magnetic cir-

cuit excited by a permanent magnet and having pole pieces defining an air gap, a magnetic vane armature movably supported in said gap, means for resiliently biasing said armature to a neutral position of maximum reluctance in the flux path across said air gap, and an exciting winding which, when energized, polarizes said armature causing it to turn against its bias to a lower reluctance position, said magnetic circuit containing an additional appreciable and intentional 10 air gap for the purpose of minimizing the permanent magnet flux change in said magnetic circuit which is due to the movement of said armature to a lower reluctance position.

2. A galvanometer having a magnetic circuit 15 containing an armature air gap and a permanent magnet for producing a flux across said air gap, a magnetic vane armature pivoted in said air gap, said vane being resiliently biased to a neutral maximum reluctance position with respect to the permanent magnetic flux crossing said gap, and an exciting coil which, when energized, polarizes said vane causing it to turn from a neutral maximum reluctance position against its bias to an unstable lower reluctance position 20 with respect to the permanent magnet flux crossing said air gap, said magnetic circuit including additional appreciable and intentional air gaps to minimize the change in reluctance of the magnetic circuit caused by such movement of 30 said armature.

3. A galvanometer comprising, soft-iron pole pieces separated by an air gap, a permanent magnet for producing a unidirectional flux between said pole pieces across said gap, a magnetic 35 vane armature pivoted in said air gap, a spring biasing said armature to a neutral position of maximum reluctance with respect to the permanent magnet flux crossing said gap, said armature being movable in opposite directions from such position to lower reluctance positions including positions where it may bridge said pole pieces, an exciting winding which, when energized, polarizes said magnetic vane armature causing it to turn from its neutral position to intercept more of the permanent magnet flux 40 crossing said gap and lowering the reluctance of said magnetic circuit, and nonmagnetic spacers between said permanent magnet and said soft-iron pole pieces for the purpose of minimizing 45 the change in reluctance of the magnetic circuit due to such movement of said armature.

4. A galvanometer comprising, pole pieces separated to form an armature air gap, a permanent magnet forming with said pole pieces a magnetic circuit for producing a unidirectional flux across 50 said gap, a magnetic vane armature pivoted at its center in the center of said gap, resilient means for biasing said vane to a neutral maximum reluctance position with respect to the flux crossing said air gap but permitting the vane to turn in either direction from such position to lower reluctance positions including positions where the vane may bridge said pole pieces, the permanent magnet being of horseshoe shape and 55 being magnetically spaced from the pole pieces by reluctance gaps permitting a substantial leakage flux between its pole pieces which does not cross the armature air gap, and a coil which, when energized, polarizes the magnetic vane armature and causes it to deflect from its neutral 60 position.

MARVEL W. SCHELDORF.
